UNITED STATES PATENT OFFICE.

CHARLES S. BURTON, OF OAK PARK, ILLINOIS.

PRIMER FOR INTERNAL-COMBUSTION ENGINES.

Application filed January 16, 1922. Serial No. 529,462.

To all whom it may concern:

Be it known that I, CHARLES S. BURTON, a citizen of the United States, residing in Oak Park, in the county of Cook and State of Illinois, have invented certain new and useful Improvements in Primers for Internal-Combustion Engines, of which the following is a specification, reference being had to the accompanying drawings, forming a part 10 thereof.

The purpose of this invention is to provide an improved construction of primer for an internal combustion engine which shall be simpler and more economical in manufacture 15 than devices now in use. It consists in the elements and features of construction shown and described, as indicated in the claim.

In the drawings:

The figure is an axial section of a device 20 embodying this invention.

This device consists of a simple plunger pump comprising the barrel, 1, plunger piston, 2, having an operating stem, 3, to which a plunger head is connected yieldingly, a 25 compressible spring, 4, reacting between the stem and the plunger head for holding the plunger head yieldingly extended for a purpose which shall hereafter appear. The intake which leads from the source of fuel 30 supply—which may be the carburetor or vacuum tank or other reservoir—is controlled by a one-way seating valve which in the construction shown is a ball valve, 5, for which a widely tapering approach to its seat is provided as seen at 6. The outlet passage, 7, 8, comprises also a valve chamber, 9, intermediate the two parts, 7 and 8, in which there is the outwardly-opening check valve, 10, which is shown as a ball valve and provided with a light spring, 11, for insuring its 35 normal seating. A cross pin, 12, may be provided to prevent it from becoming seated in or obstructing the entrance to the portion, 8, of the outflow passage. It will be understood 40 that the outflow passage is connected to the manifold of the engine to be served.

The operation of the device is that by the 45 retracting stroke of the piston plunger the fuel is drawn in past the inlet check valve, 5, and by the forcing stroke the liquid is forced on past the outlet valve to the manifold.

In devices which are commonly in use, it has been judged necessary to provide a third valve which is seated between the inlet and outlet valves by the final movement of the 55 piston in its forcing stroke, to prevent suction from the engine drawing fuel at all times through the priming device. In the present construction this third valve is rendered unnecessary by the positioning of the 60 plunger with respect to the inlet valve so that the plunger locks said inlet valve on its seat at the limit of the stroke.

Avoidance of the danger of jamming the 65 inlet valve on its seat in this forcing stroke which locks the valve, as stated, is the purpose of the yielding connection of the terminal of the plunger with the stem. The parts are designedly proportioned so that the forcing stroke of the plunger is stopped by 70 the handle, 3^a, reaching the cap of the pump barrel before the limit of the play of the plunger terminal with respect to the stem is reached, so that the force with which the plunger terminal presses and holds the 75 valve 5, to its seat, is limited by the tension which is given the spring by compressing it in the plunger stroke stopped, as indicated, by the handle reaching the gap.

I claim:—

A primer for internal combustion engines 80 consisting of a plunger pump having one-way seating valves at the intake and discharge, the plunger being positioned with respect to the intake valve for locking said 85 valve on its seat at the limit of the forcing stroke of the plunger and having a terminal for encountering the valve which is connected to the plunger for longitudinal play thereon; a spring reacting between the 90 plunger stem and said terminal to thrust the latter yieldingly against the valve; and means for stopping the positive thrust of the plunger short of the limit of the play of the terminal whereby the pressure of the 95 valve on its seat is limited to the tension of the spring.

In testimony whereof, I have hereunto set my hand at Chicago, Illinois, this 12th day of January, 1922.

CHARLES S. BURTON.
